DESIGN FOR A LIGHTING FIXTURE

Wilfrid Paul Heath, Richmond Beach, Wash.

Application April 12, 1940, Serial No. 91,639

Term of patent 7 years

To all whom it may concern:

Be it known that I, Wilfrid Paul Heath, a citizen of the United States of America, residing at Richmond Beach, King County, Washington, have invented a new, original, and ornamental design for Lighting Fixtures, of which the following is a specification, reference being had to the accompanying drawing, forming part thereof, wherein—

Fig. 1 is a perspective view of a lighting fixture embodying my new design.

Fig. 2 is an end elevation of the same.

Fig. 3 is a side elevation thereof.

The bottom and side panels of the fixture illustrated are made of translucent material.

I claim:

The ornamental design for a lighting fixture, as shown and described.

WILFRID PAUL HEATH.
